[57] **CLAIM**

The ornamental design for an ear of corn shaped bottle, as shown and described.

DESCRIPTION

FIG. 1 is a front elevation view of an ear of corn shaped bottle showing my new design, the opposite side being a mirror image;

FIG. 2 is a side elevation view thereof, the opposite side being a mirror image;

FIG. 3 is a top plan view thereof;

FIG. 4 is a bottom plan view thereof; and,

FIG. 5 is a front elevation view of an alternate embodiment of FIG. 1, the difference being in no twist cap, the broken lines are for illustrative purposes only and form no part of the claimed design.
